UNITED STATES PATENT OFFICE.

THOMAS B. STEPHENSON, JR., OF BRISTOL, CONNECTICUT, ASSIGNOR TO SESSIONS CLOCK COMPANY, OF BRISTOL, CONNECTICUT, A CORPORATION.

DESIGN FOR A CLOCK-CASE.

No. 37,603.

Specification for Design.

Patented Oct. 31, 1905.

Application filed September 15, 1905. Serial No. 278,679. Term of patent 7 years.

To all whom it may concern:

Be it known that I, THOMAS B. STEPHENSON, Jr., a citizen of the United States, residing at Bristol, in the county of Hartford and State of Connecticut, have invented a new, original, and ornamental Design for Clock-Cases, of which the following is a specification, reference being had to the accompanying drawing, forming part thereof.

The figure is a perspective view of a clock-case, showing my new design.

I claim—

The ornamental design for a clock-case, as shown.

THOMAS B. STEPHENSON, JR.
